UNITED STATES PATENT OFFICE.

HIRAM D. CURRIER, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

TELEPHONE SYSTEM.

Application filed October 5, 1918. Serial No. 257,052.

To all whom it may concern:

Be it known that I, HIRAM D. CURRIER, a citizen of the United States of America, residing at Chicago, in the county of Cook and State of Illinois, have invented certain new and useful Improvements in Telephone Systems, of which the following is a specification.

My invention relates to telephone systems wherein parties at substations may establish 10 connections between each other without the intervention of telephone exchange equipment, such systems being commonly known as intercommunicating or interior systems.

In systems of the above described type it has heretofore been necessary to furnish each subscriber with a key device having a key 15 for each other subscriber in the system. It will be at once apparent that such a system is limited to a small number of subscribers owing to the prohibitive cost and size of a key device of such size as to make it possible to have over, say about twenty subscribers in the system.

It is an object of my invention to so arrange 20 the key device that an ordinary device having ten keys or plungers may serve as many as one or two hundred subscribers. I divide the subscribers into groups of ten and have 25 a group or tens selecting brush that is capable of selecting any desired group of ten subscribers and which associates with the selected group the key device, which device may then be operated to select the particular 30 subscriber wanted in the selected group.

Another feature of my invention is the arrangement of a system as just described, so 35 that the number of subscribers may be increased at any time by merely adding new tens sections to the key device. The addition 40 of these sections does not increase the actual size of the key device. These features as well as others will be more fully described in the ensuing specification, and in the appended claims.

Referring now more particularly to the accompanying drawings in which I illustrate my invention and in which like reference characters in the different views denote like 50 parts and in which:

Fig. 1 is a side view of the combined key and switch unit with parts broken away to show the construction.

Fig. 2 is plan view of Fig. 1.
55 Fig. 3 is a left side view of Fig. 1.

Fig. 4 is a section view along the line 4-4 of Fig. 2.

Fig. 5 is a plan view of the switch unit with the enclosing casing broken away to more clearly illustrate its structure.

Fig. 6 is an end view of Fig. 5.

Fig. 7 is a left side view of Fig. 6, with the casing broken away, and

Fig. 8 is a sectional view along the line 8-8 of Fig. 5.

Referring now more in detail to my invention as illustrated, it comprises a top plate 1 through which the plungers 2 extend, each plunger 2 carrying a rectangular metal washer 3 which acts as a stop to limit the upward movement of the plungers 2. A rectangular cushion member 4 is placed between the plate 1 and the washer 3 to act as a cushion when the plungers 2 are released and return to normal.

At each end of the bank of keys K, I provide end plates 5 which are suitably fastened to the plate 1 by means of screws. The said plates 5 are provided with angular extensions 6 by which the plates 5 are secured to a suitable base 7 by means of screws 8, which screws have screw-threaded engagement with base 7. Mounted between the plates 5 are a pair of metallic mounting strips 9 suitably fastened to the end plates 5. The said strips 9 carry a plurality of sets of contact springs 10, 11, 12 and 13. The contact springs 10, 11, 12 and 13 are suitably secured to the strips 9 by means of screws 14, and the springs 10, 11, 12 and 13 are suitably insulated from the strips 9 and from each other by means of strips of insulating material.

Each plunger 2 carries a cam 15 of suitable insulation material such as hard rubber, the cam being adapted to engage its respective spring contact members 11 and 12 and move them into engagement with the spring contact members 10 and 13 respectively when its associated button 16 is depressed. A button 16 is provided for each plunger 2 and is secured to its associated plunger 2 in any suitable manner as by having screw-threaded engagement with the plunger end. The spring contacts 10, 11, 12 and 13 are connected to suitable circuits of an intercommunicating system. As circuits of this kind are well known and as my invention does not relate primarily to such circuits, it is thought unnecessary to

describe these circuits in detail. The plungers 2 are provided with cylindrical shanks 17 which fit into suitable openings in the strips 9, these openings serving as bearings 5 for the said plungers 2.

The latch frame A comprises a pair of upturned bars 18, adapted to slide in suitable notches 19 in the end plates 5, and a plurality of cross strips 20 formed integrally 10 with the upturned bars 18. The cross strips 20 rest in notches 21 in the plungers 2 when the plungers are in their normal positions. When, however, one of the plungers is depressed, the cam surface 22 of the plunger 15 2 engages a cross strip 20 causing the latch frame A to move to the right (as seen in Fig. 1) until the strip 20 disengages the cam surface 22 at which time the latch frame is moved to the left thus moving the strip 20 20 into the notch 23 of plunger 2 as clearly illustrated in Fig. 1. The latch frame is forced back by spring tension such as by means of leaf springs which are actuated by the latch frame against their normal 25 tension. Any number of end springs may be provided according to the requirements of the circuits. The depression of a key plunger causes the cam 15 which is secured to the plunger 2 to engage springs 11 and 30 12 and move them to their alternate positions into engagement with contact springs 10 and 13 respectively. Each plunger has a coil spring 25 encircling its shank 17 to hold the plunger 2 in its normal position 35 with the cushion 4 engaging the plate 1. Now, if a second plunger 2 is depressed while a plunger is in its depressed position, the latch frame moves to the right as just described and this causes the strip 20 that 40 is resting in the notch 23 of the depressed key plunger to move out of the said notch 23 allowing the said plunger that is being held in indicating position, to restore to normal, and the second depressed plunger is held in 45 its indicating position by a strip 20 moving into the notch 23 of the second plunger when the latch frame moves back to the left. Thus it will be seen that depressing any of the plungers to an indicating or full de- 50 pressed position releases any of the other plungers which may have been previously locked in indicating position. The plungers are also provided with cam surfaces 26 which cam surfaces are adapted to move the 55 latch frame to the right when a plunger is moved to its fully depressed position. The engagement of cam surface 26 with the strip 20 moves the latch to the right to release any plunger that may be in its indicating 60 position, and to actuate end contact springs to bring about circuit changes in the circuits associated with the keys. A strip of insulation 30 is suitably mounted upon the end plate 5 and carries a plurality 65 of terminals 31 which serve as terminal con-

nctions. The end springs may be actuated either when a plunger is depressed to its indicating position or when operated to its fully depressed position.

Referring now to the group switch S at the right hand side of Fig. 1 and referring more particularly to Figs. 5 to 8 inclusive, it will be noted that the group switch S is provided with a mounting plate 35 provided with a flanged portion 36 by which the switch S is mounted as a unit upon the base 7 by means of screws 37, which screws have screw-threaded engagement with the base 7. The contacts of the hand-operated switch S are mounted in groups and each group is a unit assembly. A unit or a group comprises a plurality of sets of contacts 38 and 39, preferably fourteen sets, there being as many sets of contacts as there are buttons, which in the drawings are ten. The first ten sets of contacts 38 and 39 are the line contacts, while the lower four sets of contacts are provided to take care of the battery, ringing, and other circuit connections involved in an intercommunicating system. The contacts 38 and 39 are assembled to make up a group of contact sets, fourteen in number, the contacts 38 and 39 being suitably insulated from each other by means of strips of insulation 40 and each set of contacts 38 and 39 being properly spaced by means of the spacer blocks 42 which are of suitable insulation and insulate one set of contacts 38 and 39 from the next adjacent set of contacts in the group. The group is suitably secured to the mounting plate 35 by means of screws 43.

Assuming that there are 55 substations connected to the system, then with my device a standard set of ten plunger keys, as already described, is provided and in addition there will be six groups of contacts mounted upon the plate for purposes to be more fully hereinafter described. These groups are radially disposed upon the plate 35. Nuts are provided for holding the separate units to the plate 35. Associated with the groups of contacts 38 and 39 is a hand-operated shaft 45 rotatably supported and secured to the mounting plate 35 by means of a nut 46, which nut 46 has screw-threaded engagement with the threaded end of the shaft 45. The shaft 45 supports the sets of wipers 47 and 48 there being as many sets of wipers 47 and 48 as there are sets of contacts 38 and 39 which will be fourteen in number. The wipers 47 and 48 are insulated from each other by the insulation strip 50 and properly spaced upon the shaft 45 in relation to the contacts 38 and 39 by means of the blocks of insulation 51 which insulate one set of wipers from the other. A sleeve of insulating material 49 insulates the wipers from the shaft 45. The wipers 47 and 48 are clamped in position upon the shaft 45 100 105 110 115 120 125 130

between the washer 52 and the shoulder 53 of the shaft 45 by means of a clamping nut 54 which nut 54 has screw-threaded engagement with the upper threaded portion of the 5 shaft 45.

An enclosing casing or cover 55 fits over the keys and the switch S to protect the same from dust and is provided with a collar 56 secured to the cover 55 in any suitable manner and is provided with a central opening 57 of a size to receive the shaft 45 which extends through the cover 55. A finger lever 60 is secured to the shaft 45 in any suitable manner as by means of a screw 61 10 and permits the operator of the device to rotate the shaft 45 and wipers 47 and 49 into engagement with contacts 38 and 39 in the different groups.

The cover or casing 55 which also covers 20 the switch unit S has numerals from 0 to 9 to designate the number of the tens group. Should it be desired to call station 64 the handle 60 is moved until the wipers are associated with the sixth tens group and 25 then the units button 4 is depressed to call said station.

The wipers 47 and 48 are provided with circular flanged portions 65 which form contacting surfaces for commutator brushes as 30 will now be described. A pair of commutator brush wipers 66 and 67 is provided for each set of wipers 47 and 48 which brush wipers are suitably mounted upon the stud 68, which stud 68 is secured to the mounting 35 plate 35 by means of a nut 69. A sleeve of insulation 70 is slipped over the stud 68 to insulate the commutator wipers from the stud 68, the said wipers 66 and 67 being suitably insulated from each other by means of 40 an insulation strip 71 and properly spaced in relation to the wipers 47 and 48 by means of insulation blocks 72, which insulate one set from the other. There are fourteen sets of wipers 66 and 67, the wiper ends 66' and 45 67' permanently contacting with the circular body or flanged portions 65 of the wipers 47 and 48. The brush wipers 66 and 67 have terminal ends to which connections are attached. The first ten sets of wipers 66 and 50 67 are electrically connected to the ten plunger keys 2 and the other four sets of brushes are connected to battery, generator, etc. By connecting the keys 2 to the wipers 66 and 67 it makes it possible to associate the keys 2 55 with any desired tens group of subscribers. The brush wipers 66 and 67 are clamped in position on the stud 68 by means of a nut 75 which has screw-threaded engagement with the threaded end of the stud.

60 The cover 55 is secured to the plate 1 by means of screws 76, thus holding the cover against displacement. Assuming as before that there are fifty-five stations associated with the system, there would be six groups 65 of contacts 38 and 39 in addition to the tens

key plungers, and that the station 53 is wanted, all that is necessary is to grasp the lever 61 and rotate the wipers 47 and 48 upon the shaft 45 into engagement with the group of contacts numbered 5 as shown in 70 Fig. 2, and depress the key marked 3 and a connection is established with the substation 53, and by associating the keys 1 to 10 inclusively with the wipers 47 and 48 any subscriber from 1 to 55 may be called. Should the system be increased to one hundred stations, four more groups of individual group assemblies containing contacts 38 and 39 are mounted radially upon the plate 35 so that wipers 47 and 48 may engage the different 75 contacts 38 and 39 in the different groups so that with a device of my invention, it may be seen that an intercommunicating system up to one hundred line is possible without increasing the size of the apparatus. By 80 adding groups of contacts 38 and 39, as the system increases, any number of stations may be operated up to one hundred, and one key construction will serve for any size system. As illustrated, the apparatus is 85 equipped to handle one hundred lines.

While I have illustrated my invention in a specific form, I do not wish to be limited to the same, as many changes and modifications may readily suggest themselves, and I, 90 therefore, aim to cover all such changes and modifications as come within the spirit and scope of the appended claims.

Having described my invention what I 95 claim as new and desire to secure by Letters 100 Patent is:

1. A device of the character described, including a plurality of groups of passive contacts arranged to form a bank of contacts, each group of contacts comprising a separate unitary structure, a mounting member for securing said bank of contacts in position, a spindle carrying a plurality of active contacts for engaging said passive contacts when said spindle is rotated, other groups of 105 contacts arranged to form a bank and to be continuously in engagement with said active contacts, a key device including a plurality of plungers associated with said active and passive contacts, a contact controlled by each of said plungers connected with an active contact of said group of active contacts, a manually operated member secured to the end of said spindle for rotating said group of active contacts over groups of said passive 110 contacts, to rest in engagement with a certain group of said groups of passive contacts, and also for manually restoring said active contacts to their normal position, means for then operating one of said plungers to select a desired passive contact in the 115 elected group of passive contacts, mechanical mechanism whereby when one of said plungers is operated, one previously operated plunger will restore, and a cover-cap for 120 125 130

- enclosing said key device and said banks of contacts, said cover-cap provided with an opening through which said plungers extend, and also provided with an orifice for receiving the other end of said spindle to provide a bearing for said spindle to maintain said spindle and active contacts carried thereby in operative relation with said groups of passive contacts.
- 10 2. A device of the character described including a plurality of groups of stationary contacts forming a bank of contacts, each group of contacts comprising a unitary structure, a mounting member for securing said bank of contacts thereto, a rotatable shaft provided with a plurality of active contacts, said rotatable shaft having its one end rotatably secured in said mounting plate, so that said active contacts engage said passive contacts when said shaft is rotated, other groups of stationary contacts arranged to form a bank of contacts and which bank of contacts are constantly in engagement with said active contacts, a key device including a plurality of plungers associated with said active and stationary contacts, a second mounting member having said plungers mounted thereon and also to which is secured said first mounting member, a cover-cap for enclosing said key device and said active and stationary contacts, said cover-cap provided with an opening through which said plungers extend, said cover-cap provided with an orifice, a collar secured to said cover-cap in said orifice, and adapted to receive the other end of said rotatable shaft to serve as a bearing for said other end and to maintain said active contacts in operative relation with said stationary contacts, a manually operated member secured to said rotatable shaft for rotating said active contacts into engagement with a certain group of said first groups of stationary contacts, and for restoring said shaft and active contacts to normal, means for operating one of said plungers to select a desired stationary contact in the group engaged by said active contacts, and mechanical mechanism for re-
- leasing said one plunger when another of said plungers is subsequently operated. 50
3. A device of the character described including a plurality of groups of passive contacts arranged to form a bank of contacts, each group of contacts being a unitary structure, a mounting member for mounting said bank of contacts thereon, a rotatable shaft carrying a plurality of active contacts for engaging said groups of passive contacts when said shaft is rotated and having its one end rotatably secured in said mounting member in operative relation to said passive contacts, another plurality of groups of passive contacts arranged to form a bank secured to said mounting member and in constant contactual engagement with said active contacts, a second mounting member having said first mounting member secured thereto, a key device including a plurality of plungers associated with said active and passive contacts and secured to said second mounting member, a cover casing for enclosing said key device and said active and passive contacts, said cover casing provided with an orifice, a collar secured to said cover casing in said orifice, and adapted to receive said other end of said rotatable shaft to serve as a bearing and to maintain said shaft and active contacts in operative relation with said passive contacts, a manually operated member secured to said rotatable shaft for rotating said shaft for moving said active contacts into engagement with a certain desired group of said first group of passive contacts, and to restore said active contacts to normal, an indicating scale associated with said manually operated member for indicating the group of passive contacts engaged by said active contacts, and means for operating any one of said plungers to select a desired passive contact in the group of 65 passive contacts engaged by said active contacts. 70
